T. C. ALFRED

PULVERIZER

Filed Dec. 12, 1925

UNITED STATES PATENT OFFICE.

THEODORE C. ALFRED, OF LANCASTER, OHIO.

PULVERIZER.

Application filed December 12, 1925. Serial No. 75,125.

This invention relates to improvements in pulverizers or rock crushers and is especially directed to pulverizers of the type consisting of a housing including a reducing chamber, the said chamber being adapted to receive a reducer structure consisting of a plurality of swinging hammers arranged for rotation within the chamber and adapted to deliver rapid powerful blows to the material fed into the chamber so that the latter may be reduced to a finely disintegrated or pulverized form and ejected through a screened outlet provided in the bottom of the housing.

It is another important object of the invention to provide in a pulverizer of the above character a screened outlet consisting of a plurality of separable spaced and parallel bars which are adapted to be confined in the housing beneath the revolving reducer structure, and wherein provision is made to permit of the convenient adjustment, removal or replacement of the bars in an expeditious and labor saving manner and in a method devoid of structural complications.

Another object of the invention resides in the specific design of the individual swinging hammers of the rotatable reducer structure, wherein each of said hammers has the outer and opposite longitudinal edges thereof provided with a multiplicity of striated blow delivering, rock engaging surfaces, which are so formed as to present a multiplicity of rock splitting and grinding surfaces to the material engaged and at the same time to enable the hammers to be positioned in very close engagement with the screened outlet of the housing so as to enable the pulverizer to reduce the rock to a very finely disintegrated condition.

A further object of the invention rests in constructing a pulverizer so as to produce a singularly staunch and durable machine capable of withstanding the severe usage to which it is placed without breakage or damage to its operating parts, and wherein the various revolving parts of the machine are carefully balanced and distributed so as to avoid excessive vibration when the machine is in active operation.

With these and other objects in view, as will appear as the description proceeds, the invention consists in the novel features of construction, combinations of elements and arrangements of parts hereinafter to be fully

described and pointed out in the appended claims.

In the accompanying drawing:

Figure 1 is a vertical sectional view taken through a rock pulverizer constructed in accordance with the present invention, 60

Figure 2 is a vertical transverse sectional view taken on the planes indicated by the line 2—2 of Figure 1,

Figure 3 is a horizontal sectional view on 65 the line 3—3 of Figure 1,

Figure 4 is a similar view on the line 4—4 of Figure 1,

Figure 5 is a detail perspective view of one of the swinging hammers utilized in the reducer structure of the pulverizer, 70

Figure 6 is a plan view of the screen bar assembly,

Figure 7 is a detail vertical sectional view showing a slightly modified form of the invention wherein the screen bars are set tangentially to the axial center of the hammer structure, 75

Referring more particularly to the drawings the numeral 1 designates my improved pulverizer comprising the present invention in its entirety. This pulverizer comprises generally a housing comprising spaced, parallel vertically disposed side plates 2, preferably of heavy cast metal. The bottom edges of these plates terminate in smooth horizontal surfaces 3, so as to provide a base permitting of the support of the housing upon any desired supporting structure which may or may not be portable. The inner surface of the plates 2 are provided with registering recesses 4, which are adapted to receive the ends of a multiplicity of transversely extending chill sections 5, which act to space the side plates 2 and are securely retained in the recess 4 by the provision of transversely extending binding rods 6. Certain of the ends of these rods are provided with nuts which when tightened serve to draw the plates 2 together and frictionally engage the same with the ends of the sections 5, so that said plates in conjunction with the sections 5 may be rigidly united to present a composite, unitary structure, 90

The sections 5 are disposed in such relation to the side plates 2 as to produce an internal reducing chamber 7, having an open upper end 8, constituting an entrance permitting of the feeding of material to be ground into said chamber. If desired the 110

entrance 8 may be provided with an adjustable feeding trough 9 facilitating the entrance of material into said chamber. Also, by adjusting the trough 9 longitudinally the effective width of the entrance 8 may be controlled in order that materials may be fed into said chamber which do not exceed a predetermined size. The inner surface of the sections 5 are corrugated as at 10 so as to facilitate the breaking up of the material within the chamber 7 as such material is subjected to the disintegrating action of the rotating reducer structure 11.

This structure, in its present embodiment, 15 consists of a shaft 12, extending transversely through the housing and supported for rotation in bearings 13, provided in connections with bearing sections 14 secured to the outer surfaces of the side plate 2. One 20 end of the shaft 12 is extended beyond its adjacent bearing to receive a pulley 15 by which power may be imparted from any suitable source, to the shaft. The opposite end of the shaft is equipped, beyond its 25 adjacent bearing, with a fly or balance wheel 16. The bearing sections 14 are of sufficient diameter to cover openings 17 provided in the side plates 2, and arranged for rotation within these openings and keyed to the shaft 30 12 are the end plates 18 of the reducer structure. These plates carry fixed transversely extending rods 19, upon which are rockably mounted a plurality of swinging hammers 20.

Each of these hammers, as disclosed in 35 Figure 5, comprise an enlarged head portion 21, which terminates in inwardly disposed ears 22, that are apertured as at 23 for the reception of the rods 19. By reference to Figure 2 of the drawings it will be 40 noted that the length of each of the hammers 20 corresponds substantially to the width of the chamber 7, and that the end plates 18 are arranged in the openings 17, so that said end plates will not interfere with the free 45 swinging action of the hammers. By this construction the hammers may swing about their individual pivots provided by the rods 19, so as to either project beyond or lie within the outer diameter of the plates 18. In 50 other words the hammers are permitted to have an independent swinging movement with respect to the bodily rotation of the reducer structure as a whole. An important feature of the present invention consists in 55 providing the head portion 21 of each hammer along the opposite outer longitudinal edges thereof with a plurality of striated striking surfaces 24, and it is these surfaces that receive the major impact and wear which results from the operation of the pulverizer. By providing the surfaces 24 the hammers each present a multiplicity of cutting or splitting edges to the material under process of disintegration, so as to facilitate said process and to produce

more finely divided or disintegrated material. It is important in the design of pulverizers of this type in securing most efficient results, to form the hammers as large as practicable so that they will have 70 adequate weight and strength to accomplish the work for which they are employed. An inspection of Figure 1 will disclose that the bounding wall of the chamber 7 is of curved 75 arcuate formation, whereas the outer surfaces of the hammers 20 are substantially flat. Due to this dissimilarity in design, if the head portions 21 were not provided with the striking surfaces 24, the said hammers would either engage the outer wall of the 80 chamber at its point of nearest approach, or the hammers would have to be set in closer to the shaft 12 so as to provide adequate clearance. This is the common practice and results in causing the hammers to be spaced 85 so far from the wall of the chamber as to produce coarsely pulverized material, whereas in the present design, the stepped formation of the head 21 of each hammer enables the latter to be set out closely to the bounding wall of the chamber to produce finely pulverized material and at the same time a construction is present wherein each of the hammers is of adequate weight to withstand 90 its intended service. If desired, the end plates 18 may be provided with reserve openings 25 for the reception of the rods 19, which latter openings are set out from the diameter of the reducer structure a slightly 95 greater distance than the openings which initially receive the rods 19. This is done in order to compensate for wear on the head portions of the hammers. Also, the hammers themselves are reversible to present new cutting edges after the initial set of 100 edges have been worn to a predetermined extent.

In the design of the hammers it is preferable to provide the same with pockets 26 in which may be placed lead or the like 27. 110 This is done in order to obtain a true balance of the rotatable reducer structure. Ordinarily the hammers are formed from manganese steel and it has been found in practice that the hammers vary appreciably in 115 weight. Therefore, before the same are completely assembled each hammer is weighed individually and enough additional material is added to the pockets 26 so as to bring each of the hammers up to exactly a 120 required weight. By employing this method the pulverizer when in operation runs very smoothly, in a manner totally devoid of unnecessary wear and vibration. This feature also results in the production of ground rock 125 of a uniform character. This balance feature is also carried out in the end plates and fly wheel.

Another of the outstanding features of the invention rests in the specific construc-

tion of the screened outlet 28 of the pulverizer. This outlet is arranged below the reducer structure and in its preferred embodiment consists of a plurality of parallel, spaced transversely extending steel bars 29, which have their ends arranged in the recess 4 provided in the inner walls of the side plates 2. These bars are each separably positioned within said recess and are spaced transversely by the employment of spacers 30, which may be of any suitable gauge so as to control the width of the spaces existing between said bars. The inner edges of said bars are arranged in a circle having an axis eccentric to that of the shaft 12 in order, as shown in Figure 1, that a gradually diminishing grinding space will be provided between the outer paths of rotation of the hammers 20 and the inner surfaces of the bars 29.

To remove the bars from or place the same within the housing, the latter is provided with a laterally disposed clean-out opening 31 which is adapted to receive removably a door 32. The inward movement of this door is limited by shoulders 33 provided on the side plates 2, and the door may be retained in engagement with said shoulders through the instrumentality of strips 34, bolted or otherwise secured as at 35 to the side plates. Obviously, when the strips 34 are removed the door may be moved horizontally and outwardly so as to provide access to the interior of the housing. The inner surface of the door may be corrugated as at 36 for cooperation with the reducer structure, these corrugations being complementary to the corrugations 10.

Embedded in recesses 37 provided in the side plates is a pair of transversely extending bolts 38 which act to receive in a slidable manner the outer lug extensions 39 provided on a wedge member 40, the said bolts 38 being provided with nuts 41, which when tightened engage the wedge member so as to force the latter inwardly so as to bring the inclined longitudinal edge 42 thereof into engagement with the upper of the bars 29. It will be observed that the upper or outer-most of the bars 29 is positioned in the ends of the recesses provided therefor in the side plates 2 and can not be moved to any higher distances or positions. Therefore, as the wedge member enters the strips, as shown in Figure 1, and advanced by pressure, the said bars will be securely clamped in tight compressed relationship so as to provide for proper spacing between the bars and subsequent discharge of the pulverized material from the bottom outlet 43 of the pulverizer. The wedge member 40 is supported within a casing 44 carried by the side plates, and the top of the casing is readily removable to afford access to the nuts 41, so that the bars may be tightened while the

machine is in operation. When the door 32 is removed, and the wedge member 40 loosened, it will be seen that there is sufficient play in the mounting of the bars 29 to permit the operator to withdraw the same from the housing by way of the cleanout opening 31. In this manner repairs and replacements of the bars may be made in a convenient manner permitting of the withdrawal of the bars from the housing through said clean-out opening. It will be observed, however, that the door 32 itself does not exercise any clamping or holding action on the individual base of the screen.

In view of the foregoing description taken in connection with the accompanying drawing it will be seen that the present invention provides a pulverizer particularly adapted for the grinding of lime stone which may be useful in an agricultural sense for both fertilizing and for curing land that is sour. The machine has been designed with the end in view of providing a pulverizer of large capacity, staunch and durable construction and one particularly where repairs and adjustments may be made when required with facility and convenience. While the above description refers to a specific form of the present invention it will be appreciated, however, that the invention is not limited to the precise details of construction above set forth, except as hereinafter defined in the following claims.

For example, the screen bars 29, as shown in Figure 7 may be set tangentially with respect to the center of the shaft 12, so that sharp edges will be presented to the rotating hammers, instead of the smooth flat surface presented, as is the case in the preferred form of the invention.

What is claimed is:

1. In a pulverizer, a housing including a pulverizing chamber, a reducing rotor mounted for rotation about a fixed axis disposed within said chamber, an outlet screen for said chamber consisting of a plurality of spaced transversely extending parallel bars having the ends thereof positioned within recesses provided in the side walls of said housing, a wedge member slidably mounted in connection with said housing, means permitting of the adjustment of said wedge member so as to place said bars under compression, and a removable door carried by said housing above said wedge member and mounted in said housing independently of said wedge member.

2. In a pulverizer, a housing including a pulverizing chamber having a material inlet in the upper part thereof and an outlet in the lower part thereof, a reducing rotor mounted for rotation within said chamber, a screen for controlling the release of material from said chamber through said outlet, said screen consisting of a plurality of in-

dividually separable transversely extending bars, having the ends thereof movably positioned within arcuate recesses provided in the inner walls of said housing, the ends of 5 said bars being engaged by spacing means to maintain the sides of the bars in predetermined spaced relationship, a wedge member having an inclined surface arranged to be forced between certain of said bars so as to 10 force said bars toward the ends of said recesses and maintain the same in compressed rigidly clamped relationship, adjusting means permitting of the advance or retraction of said wedge into and out of engagement with said bars, said housing being provided with a clean-out opening above said bars providing access to said chamber and through which opening said bars may be removed from or inserted into said chamber,

and a closure for said opening mounted in 20 connection with said housing so as to be independent of said bar mounting and adjustment.

3. In a pulverizer, a housing including a 25 rotor chamber provided with a material entrance and outlet, a reducing rotor mounted in said chamber for rotation about a fixed longitudinal axis, a screen arranged over said outlet and beneath said rotor, consisting of a plurality of spaced parallel bars arranged to extend transversely across said outlet, means for supporting said bars at the ends thereof, and an expansion device 30 cooperative with said bars to retain the latter against movement in their operative positions.

In testimony whereof I affix my signature,
THEODORE C. ALFRED.
